UNITED STATES PATENT OFFICE.

LEO P. UPHOFF AND FLOYD A. SIMS, OF SAN JOSE, CALIFORNIA.

VALVE.

Application filed December 9, 1926. Serial No. 153,569.

Our invention relates particularly to a valve for use in connection with an internal combustion engine and rendered operative by the inhalation of air into the engine cylinder and by the exhalation of the air therefrom.

It is one object of the invention to provide a valve of the character indicated that may be readily substituted for the spark plug in the engine cylinder.

It is another object of the invention to provide a valve of the character indicated that will be simple in form and construction, economical to manufacture, of few and simple parts, positive in action, and highly efficient in its practical application.

In the drawing:

Figure 1 is a longitudinal section through our improved valve and showing in dotted lines a portion of the engine on which it is mounted.

Figure 2 is a sectional view on line 2—2 of Figure 1.

Figure 3 is a sectional view on line 3—3 of Figure 1.

Referring now more particularly to the drawing, we show at 1 a cylindrical housing divided into two chambers as 2 and 3 by a partition 4 provided with an orifice 5 connecting the two chambers.

One end of the cylinder is provided with a shoulder 6, and seated on this shoulder 6 is a plate 7 provided with a shoulder 8. The plate is securely mounted in position by rolling the edge of the cylinder over the edge of the plate 7 to engage the shoulder 8 as clearly shown in Figure 1. The plate 7 is provided with a plurality of annular orifices 9 formed therein in concentric relation to its axis as shown in Figure 2, and with an axially arranged and outwardly extending threaded portion or tube 10 adapted to engage the threaded socket 11 in the engine cylinder 12.

Arranged in chamber 3 is a cup member 13 having an orifice 14 formed in its bottom to communicate with the tube 10. This cup member 13 functions as a valve and normally rests upon the plate 7 and closes the orifices 9, but leaves an open communication between the chamber 3 and tube 10 at all times. The side wall 15 of the cup is in sliding engagement with the wall of the chamber, and a spring 16 is placed in the cup to limit its upward movement and insure its prompt return to its normal position.

The other end of the cylinder is provided

with a shoulder 17, and seated on this shoulder is a plate 18 provided with a shoulder 19. The plate is securely held in position by rolling the edge of the cylinder over the edge of the plate 18 to engage shoulder 19. The plate 18 is provided with an axially arranged and outwardly extending tube 20 communicating with the chamber 2 and adapted to receive one end of a hose not shown.

Arranged in chamber 2 is a cup member 21 having a plurality of small orifices as 22 formed therein and arranged in a circle concentric to the axis of the plate. This cup member 21 functions as a valve and normally rests on the partition 4 and closes off the chamber 2 from the chamber 3. The side wall 23 of the cup is in sliding engagement with the wall of the chamber, and a spring 24 is placed in the cup to limit its upward movement and insure its prompt return to its normal position.

This valve is particularly adapted for use in connection with a spraying outfit where a supply of air under pressure is used through a nozzle for atomizing a paint or similar substance and depositing the same on a desired surface.

In its practical application the spark plug is removed from the engine cylinder and the threaded tube 10 of the device inserted in the socket 11 vacated thereby. Now, when the piston 25 moves outwardly in the cylinder 12 the suction caused thereby tends to create a vacuum in the chamber 3 and consequently the cup member or valve 21 is drawn down even more tightly on its seat but the cup or valve 13 is raised from its seat and air is drawn into the chamber through the orifices 9, the engine cylinder 12, tube 10 and chamber 3 being filled with air under atmospheric pressure. Upon the inward stroke of the piston the air pressure in chamber 2 is immediately increased thereby forcing valve 13 down more tightly upon its seat and raising the valve 21. The air previously drawn into the cylinder is now driven through chamber 2 and out through tube 20 to be used for the desired purpose, passing through the orifices 22 or any other passage that might be provided.

It may now be seen that we have provided a device that is small and compact, that is economical to manufacture, that offers free passage of the air in both directions as described, that consists of few parts, is durable,

2
and highly efficient in its practical application.

It is to be understood, of course, that while we have herein shown and described 5 but one specific embodiment of our invention, changes in form, construction, and method of operation may be made within the scope of the appended claims.

We claim:—

- 10 A valve comprising a hollow cylindrical body portion provided with a transversely positioned partition intermediate its ends and having an orifice therein, an apertured plate mounted in one end of the body portion and provided with an axially extending tube adapted to engage a spark plug aperture in an internal combustion engine, a
- 15

check valve operatively mounted to normally close said apertures in said plate but movable to permit the entrance of air into said body 20 portion and having an orifice formed therein communicating with said tube, a plate mounted in the other end of said body portion and provided with an axially extending tube adapted to engage a hose, and an apertured valve member operatively mounted to normally close the orifice in said partition but movable relative thereto whereby to establish communication between the orifice in said partition and the apertures in said 25 valve member.

LEO P. UPHOFF.
